UNITED STATES PATENT OFFICE.

ARTHUR N. BLAKE, OF IREONTON, OHIO, ASSIGNOR TO NEW METHOD STOVE COMPANY,
OF MANSFIELD, OHIO, A COPARTNERSHIP.

DESIGN FOR A RADIANT GAS HEATER.

Application filed June 5, 1922. Serial No. 2,537. Term of patent 3½ years.

To all whom it may concern:

Be it known that I, ARTHUR N. BLAKE, a citizen of the United States, residing at Ironton, in the county of Lawrence and State of Ohio, have invented a new, original, and ornamental Design for a Radiant Gas Heater, of which the following is a specification, reference being had to the accompany-

ing drawing, forming part thereof, in which the figure is a front elevation of a radiant gas heater embodying my invention.

I claim:

The ornamental design for a radiant gas heater, as shown.

ARTHUR N. BLAKE.
